OVEN FURNACE

William R. Hones, Baldwin, N. Y., assignor to
 Charles A. Hones, Inc., Baldwin, N. Y., a corporation of New York

Application May 23, 1938, Serial No. 209,430

3 Claims. (Cl. 263—43)

This invention relates to an oven furnace.

The object of the invention is the production of a furnace by means of which high temperatures can be obtained with atmospheric burners that do not require high pressures.

The second object of the invention is the production of a furnace to heat treat steels or heat other materials, with burners that depend on the pressure in the mains, often as low as two inches of water column to induce the air into the furnace for combustion.

Other objects will be apparent from the specification and claims.

In the accompanying drawings Fig. 1 represents a front view of an exemplification of the oven furnace; Fig. 2 shows a right hand view of Fig. 1 partly broken away; Fig. 3 indicates a top view of the furnace; Fig. 4 represents a section of Fig. 1 on line 4, 4; Fig. 5 shows a section 20 of Fig. 2 on the line 5, 5; Fig. 6 is a section of Fig. 2 on the line 6, 6; Fig. 7 is a partial front view of the furnace with a modification; Fig. 8 shows a partial section of Fig. 7 on the line 8, 8 and Fig. 9 indicates a partial top view of Fig. 7.

The oven furnace in this exemplification is indicated to comprise the following.

The shell of the furnace is shown with its front plate 20 and its rear plate 50.

The front plate 20 has integral with its top and bottom ends the flanges 21 and 22. Side flanges for the front plate 20 are shown at 23 with the projecting lugs 24. Front legs 28 extend from the lower ends of the front plate. A furnace door opening 30 is indicated in the plate 20 and is shown with horizontal flanges 31 and vertical flanges 32 which form the bead 33 for the front plate.

A horizontal flange 43, extends from the rear face of the front plate 20, and a shelf bracket 45 extends from the front face thereof.

The rear plate 50 has integral therewith the top flange 51 and the bottom flange 52, which are connected by the side flanges 53. An opening 54 is shown in the plate 50. A rear leg 58 extends 45 from the bottom flange 52. Projecting lugs 59 extend from the flanges 53. A horizontal flange 63 extends from the inner surface of the rear plate 50. A clamping rod 65 extends through each pair of projecting lugs 24 and 59 which with their threaded ends and nuts as shown maintain the plates 20 and 50 in operative position. A supporting plate 66 with the opening 67 is supported on the flanges 43 and 63.

The heating chamber for the furnace is indicated at 70. The walls of the heating chamber

are composed of insulating fire brick of medium heat storage and low conductivity. They have low expansion characteristics because of the high temperature required in the furnace.

The heating chamber 70 of the furnace comprises the side walls 73, with the conduits 74, at the lower portions of their inner faces, the said conduits having the upper deflecting faces 75, latter incline upwardly toward the axial center of said heating chamber. The conduits 74 provide a large volume for the combustion of the gases in the heating chamber, and also deflect the said gases to prevent them flowing straight upwardly along the side walls of said heating chamber, during their flow out of said furnace 10 and before impregnating the objects treated in the heating chamber.

The bottom wall of the heating chamber 70 is indicated at 76 with the opening 77, which latter with opening 67 produces a passage for the introduction of the required volume of air into said heating chamber 70 to support combustion.

The top wall of the heating chamber 70 is indicated at 80 with the inclined lower faces 81 and the upper projection 83 with the outlet flue 84.

The rear wall of the heating chamber 70 is indicated at 85 with the opening 87 extending therethrough. The front wall of the heating chamber is shown at 88.

At the upper end of the heating chamber 70 is indicated the triangular shaped hood 92, the ends 93 of which extend into the side walls 73. The upper converging faces 94 of the hood 92 form with the faces 81 of the top wall of the heating chamber the converging outlet conduits 95.

The upper and smaller ends of the conduits 95 join with the outlet flue 84.

The sizes and shapes of the outlet conduits 95, are important for holding back the gases of combustion until they have imparted their heat to the heating chamber and its contents. The two conduits 95 are provided to evenly heat the front and rear of the heating chamber. The hood 92 also functions as a heat deflector. The hood 92 with its conduits 95 function to produce an equilibrium or evenness of temperature in the heating chamber 70, which is important and essential to the successful operation of the furnace.

The fire brick walls of the heating chamber 70 are covered by insulating walls preferably of magnesia content, and are indicated with the side members 100, the rear member 101 having the opening 102 and the top member 103. The top and side members of the insulating walls are

- covered by the jacket 105 of sheet steel. The said jacket prevents heat loss, and is not heated to a high temperature which would result in poor working conditions, and subject the operators of the furnace to burns. A flue 106 extends through the jacket 105 and connects with the flue 84.
- The opening 30 of the front plate 20 of the furnace is provided with the door having the front wall 110 with the rearwardly projecting flanges 111 and 112. The latter bear against the bead 33 of the opening 30 when the said door is closed. The door between its flanges 111 and 112 supports a block 115, which may comprise a number of members, of insulating fire brick of the same material as described for the walls of the heating chamber 70. The said block 115 bears against the front wall 110 of the door and projects beyond its flanges. The top and bottom ends of the block 115 bear against the adjacent flanges 31 of the plate 20, and its side faces 116 are tapered to allow the door to be easily swung to its open or closed position. A handle 118 is provided for the wall 110 to easily swing the door. To the front wall 110 of the door of the furnace are fastened a pair of U shaped brackets 120 having the horizontal members 121 and 122. The front plate 20 of the furnace has fastened thereto the pair of brackets 125 by means of screws or other means not shown.
- Each of the brackets 125 has integral therewith the upper supporting lug 129, and the lower supporting lug 130. A pair of hinge rods are indicated, with each having the upper vertical member 132, the lower vertical member 133, and the horizontal connecting member 135. The members 132 are threaded at their upper ends for the nuts 136 and the members 133 are threaded at their lower ends for the nuts 138. The member 132 of each hinge rod extends through openings in the lugs 129 and 130, and the member 133 of each hinge rod extends through openings in the horizontal members 121 and 122 of the brackets 120. The members 132 of the hinge rods are vertically supported by the nuts 136, and the brackets 120 with the nuts 138 support the members 133 of the hinge rods. By means of the handle 118 and the hinge rods, the door having the front wall 110 can be easily positioned in its open position, see Fig. 1, as indicated in dotted lines, distant from the furnace door opening 30.
- Upon the flanges 22 and 52 of the front plate 20 and rear plate 59 respectively of the furnace, is supported the burner supporting plate 145. Upon the plate 145 are supported a plurality of Venturi Bunsen burners 146, operating at slightly above the atmospheric pressure and which are connected by the connecting portions 147, and have integral therewith the flanges 148 and the latter are bolted to the plate 145. The valve for each burner is indicated at 149. The outlet ends of said burners lead to the openings 67 and 71. It will be noted that each of the burners is fitted with an inspirator. When the burners are functioning the openings 67 and 71 permit a proper volume of air to mix with the outlet fuel of said burners for combustion.
- A supply pipe for fuel for the burners is shown at 150.
- A table or hearth 151 for supporting the material to be treated and of highly refractory material, preferably of carborundum and the like, is supported upon the bottom wall 76 of the heating chamber 70. The sides of said hearth are opposite the conduits 74 of the side walls 73.

A pyrometer 155 is shown with the tube 156, which latter extends through the opening 87 of the rear wall 85 of the heating chamber 70 and the wall 101.

Referring to Figs. 7, 8 and 9 a modified door with its appurtenances is indicated. The front plate 20 of the furnace is again shown with its projecting lugs 24 and the pyrometer is again indicated at 155. The side walls of the heating chamber 70 are again indicated at 73 and the side members of the insulating wall are again indicated at 100.

A pair of similar supporting and guide brackets each indicated in its entirety by the numeral 160, are secured to the front plate 20 of the furnace. The said plate 20 is indicated with furnace door opening 31a, with its bead 33a. Each of the brackets 160 comprises the plate 165 which has spaced therefrom the parallel members 166 and the parallel members 167 at right angles thereto; forming the runways 168 and the runways 169 at right angles to one another. The door of the furnace is indicated at 170 with the flanges 171 and 172 at its edges. From the top of the door 170 extend the guide pins 173 and from the bottom of the said door extend the guide pins 174. A handle for the door 170 is indicated at 178.

The door 170 is opened by engaging the handle 178 and pulling it forwardly, by reason of which the door will be opened with the guide pins 173 and 174 sliding in the runways 168.

Next the said door 178 is pulled in a direction parallel to the front of the furnace with the said guide pins sliding in the runway 169, until the door 170 is positioned to one side of the furnace door opening. The plate 165 of the lower bracket 160 functions as a shelf for transferring the objects treated into and out of the heating chamber 170 of the furnace.

During the operation of the furnace the flames from the burners 146 impinge against the lower face of the hearth 151, upon which the objects being heated are placed. The products of combustion impinge against the walls of the conduits 74 and are deflected toward the middle of the chamber 70 above said hearth. The conduits 74 provide a large area for combustion adjacent to the objects being heated, deflect the gases and retard their speed to efficiently heat said objects.

Various modifications may be made in the invention and the present exemplification is to be taken as illustrative and not limitative thereof.

Having described my invention I claim:

1. In a furnace the combination of a front plate having a furnace door opening, a door for said opening, a rear plate for the furnace, brick of refractory material between said plates forming a heating chamber, U shaped brackets having upper and lower horizontal members extending from the outer face of said door, and spaced from each other, brackets spaced from each other extending from the front plate of the furnace, each of the latter brackets having projecting therefrom an upper and a lower lug, a pair of hinge rods each comprising an upper vertical member with a nut at its upper end, a lower vertical member for each hinge rod with a nut at its lower end and a horizontal member for each hinge rod connecting its vertical members, the upper vertical members of the hinge rods extending through openings in the lugs of the brackets of the said front plate and the lower vertical members of the hinge rods extending through openings in the horizontal members of the U shaped brackets of said door, the nuts at the upper ends

of the upper vertical members of the hinge rods bearing on the lugs of the brackets extending from the front plate of the furnace and nuts at the lower ends of the lower vertical members 5 of the hinge rods bearing against the lower horizontal members of the U shaped brackets.

2. In a furnace the combination of a heating chamber having side walls with conduits at the lower portions of their inner faces, said conduits 10 having upper deflecting faces which incline upwardly toward the axial center of the heating chamber, said conduits providing a large volume for the combustion of the gases in said heating chamber and deflecting said gases toward the 15 central portion of said chamber, said heating chamber having a front wall, a rear wall, a top wall with a flue extending therethrough and having inclined faces on its bottom side, said chamber having a bottom wall with an opening, a 20 triangular shaped hood at the upper portion of the heating chamber having inclined upper faces, the latter spaced from the inclined faces of the top wall and forming converging outlet conduits therewith and leading to the flue in the top wall, 25 and a hearth for material to be heated supported

upon the bottom wall of the heating chamber over the opening in said bottom walls, the sides of said hearth opposite the conduits in the side walls of the heating chamber and means to heat the said heating chamber at a low pressure.

3. In a furnace the combination of a front plate having a furnace door opening, a door for said opening, a rear plate for the furnace, brick of refractory material between said plates forming a heating chamber, brackets extending from the outer faces of said door and spaced from each other, brackets spaced from each other extending from the front plate of the furnace, a pair of hinge rods, each comprising an upper vertical member with supporting means at its upper end, 10 a lower vertical member for each hinge rod and a nut at the lower end, and a horizontal member for each hinge rod connecting its vertical members, the upper vertical members of the hinge rods extending through openings in the brackets 15 of said front plate and the lower vertical members of the hinge rods extending through openings of the brackets of said door. 20

WILLIAM R. HONES. 25
